UNITED STATES PATENT OFFICE

GEORGE E. DEAN, OF WALKER TOWNSHIP, KENT COUNTY, MICHIGAN, ASSIGNOR TO
CHARLES G. WILLETT, OF GRAND RAPIDS, MICHIGAN

SPRING GRADER AND MOLDBOARD

Application filed October 7, 1931. Serial No. 567,349.

This invention relates or pertains to a scraping mechanism adapted to be used to scrape dirt, snow or the like and more specifically this invention deals with the moldboard and its mounting whereby the moldboard, this board carrying the scraper or cutting blade, may be pivotally mounted upon the depending arm of the vehicle carrying the same, usually a grader or scraper.

One of the principal features of my invention resides in the construction of my moldboard, this moldboard being formed in two parts, namely, an upper moldboard and a lower moldboard. These moldboards are connected together only by means of my double tension spring and hence may have movement relative to each other. Thus, by separating my moldboard into two parts I am able to utilize a lower moldboard as a backing means or reinforcing means for the cutting blade whereas the upper moldboard serves in the capacity of providing an integral mounting member for the upper ends of the several double tension springs. It will be noted that the lower edge of the upper moldboard and the upper edge of the lower moldboard are closely adjacent whereby the dirt or the like will not pass therebetween. Moreover, the upper moldboard is slightly advanced forwardly of the lower one, whereby the tendency of the dirt to pass between the two moldboards will be curbed.

Also, I form the lower moldboard in two or more sections, each section supporting a cutter blade of the same length and each section being separately supported by means of springs upon the upper moldboard. Thus, as each unit cutter blade is separately mounted, any obstacle in the path of one will merely cause that particular blade to be forced upwardly and rearwardly while the others will operate as usual.

Another material feature of my invention resides in the arrangement of the several elements whereby a very compact structure is had. In this regard note that the adjusting means for the brackets are located directly behind the lower moldboard and also that these brackets do not extend above the upper edge of the upper moldboard. Thus the

structure is located in a minimum height and hence the moldboard arm, this arm serving as a supporting means therefor, may be located relatively close to the ground, thereby providing a sturdier construction.

Another advantage which I obtain lies in my adjustment for the cutting blade whereby the same may be moved downwardly relative to the lower moldboard which supports the same.

Other objects will appear, or become apparent or obvious during the description of the device shown in the accompanying drawing, in which,

Fig. 1 is a view in cross section through my novel moldboard mounting means, this view being taken along the plane of line 1—1 of Fig. 2.

Fig. 2 is a view of the mounting means taken from the rear, this being illustrated by the arrow A in Fig. 1.

Fig. 3 is a front view of one end of the cutting blade, this view illustrating the adjustment which may be made between the blade and the lower moldboard which supports the same.

Like numerals refer to like parts throughout the several views.

Referring particularly to Figs. 1 and 2, 10 designates a circle member adapted to be 80 revolvably supported upon the frame of the grader or scraper (not shown) and 11 indicates a moldboard arm depending therefrom. Only a single arm 11 is shown in the drawing but it is to be understood that at least 85 two of these arms are to be used with the circle member 10.

Bracket members are pivotally mounted on the arm 11 by means of a pin 12, having a retaining cotter key 13 therein, and only two 90 opposed bracket members are shown in the drawing although two bracket members are used with each of the depending moldboard arms 11.

Each of the opposed bracket members has 95 an upper arm 14 and a depending lower arm 25 as clearly shown in Fig. 1 of the drawing. These opposed bracket members are identical in construction except that one is right-hand and the other is left-hand.

The upper arms 14 of the opposed brackets are rigidly attached to the upper moldboard 16 as by the bolts 15. The upper moldboard extends underneath the supporting arms 11 and is of angular shape. The bracket members extend on either side of the depending arm 11. See Fig. 2.

The upper moldboard 16 is provided with clamps 17 which receive the upper ends of the double tension springs 18, the clamps being held to the upper moldboard by means of the bolts 19, these bolts having their heads countersunk. See Fig. 1.

The lower moldboards 30 consist of flat, rectangular members having clamps 31 spaced thereon in conformity with the clamps 17 on the upper moldboard 16 and the clamps 31 receive the lower curved ends of the springs 18. See Fig. 2.

20 The moldboards 30 have a series of holes 32 located therein, these holes being adapted to receive the bolts 33. The blade members 34 also have a series of holes 35 therein, these holes receiving bolts 33 as shown in Fig. 1. 25 Thus the blades 34 may be vertically adjusted to three different positions. Also, as each blade is individually carried or supported, it may flex from its normal position without disturbing the positions of the other 30 blades, these blades continuing their scraping function.

The arms 25 of the bracket member, which is pivotally mounted upon the moldboard arm 11, has a curved lower portion 36, this portion being provided with a series of openings or holes 37. The lower end of the arm 11 has a single opening in alignment with the arc which passes through the openings 37. An adjusting pin 38, having a cotter key 39, 40 is adapted to be received by one of the openings 37 and the single opening in the arm 11.

The operation of the mechanism just recited is easily understood. The pin 38 may be removed and the bracket member shifted 45 about its pivot 12 until it is at the desired angle. This angle is determined by the angle that one desires to set the scraper blade 34, this blade being set at different angles for different types of work, and next the pin 38 50 is inserted through the aligned opening and the cotter key 39 placed in position thus preventing any accidental withdrawal.

Having thus revealed this invention, I claim as new and desire to secure the following combinations and elements or equivalents thereof, by Letters Patent of the United States.

I claim:

1. In combination, a support, a bracket 60 pivotally connected to said support, an upper moldboard attached to said bracket, a lower moldboard, spring means connecting the lower moldboard to the upper moldboard, a blade member attached to said lower moldboard and means for adjusting the bracket relative

to its support whereby the position of the blade is varied.

2. In combination, an upper moldboard having a depending flange portion, a lower moldboard comprising two separate sections extending beneath the upper moldboard, separate cutter blades attached to their corresponding sections and spring means connecting the respective sections to the upper moldboard. 70

3. In a device of the character described, an upper moldboard, a support, means connecting the upper moldboard to the support, a lower moldboard and spring means interconnecting the lower moldboard to the upper moldboard, said moldboards lying in substantially the same plane. 75

4. In a scraping mechanism, the combination of, a support, a bracket member pivotally connected to the said support, said bracket member having a laterally extending arm, an upper moldboard depending from and rigid with said arm, a lower moldboard, a cutting blade rigidly attached to said lower moldboard, spring means interconnecting the lower and upper moldboard, and means for locking said bracket member to its support. 80

In testimony whereof I affix my signature.

GEORGE E. DEAN.
